Fig. 5

FIG. 1 is a front-perspective view of a housing for a data set or similar article showing my new design;

FIG. 2 is a front-elevation view thereof;

FIG. 3 is a left-side view thereof;

FIG. 4 is a partial sectional view thereof, taken through the faceplate thereof along lines 4—4 in FIG. 2; and

FIG. 5 is a rear view thereof.

The broken line representations of conventional buttons, cable, connectors, fuse caps, switch, and foot rests in FIGS. 1, 3 and 5 are for purposes of illustration only, my new, original, and ornamental design being shown in solid lines. The undisclosed side of the housing is essentially a mirror image of the side that is shown.

I claim:

The ornamental design for a housing for a data set or similar article, as shown and described.
